UNITED STATES PATENT OFFICE.

FRANZ X. WAGNER, OF NEW YORK, N. Y., ASSIGNOR TO STEPHEN T. SMITH, OF SAME PLACE.

CUT-OFF FOR GAS-BURNERS.

SPECIFICATION forming part of Letters Patent No. 374,096, dated November 29, 1887.

Application filed January 20, 1887. Serial No. 224,897. (No model.)

To all whom it may concern:

Be it known that I, FRANZ X. WAGNER, a citizen of the United States, residing at New York, in the county and State of New York, have invented new and useful Improvements 5 in Cut-Offs for Gas-Burners, of which the following is a specification.

My invention relates to improvements in devices for cutting off the supply of gas to the burner when the jet has been extinguished without turning a cock to shut off the gas-supply thereto; and said invention consists, essentially, in the combination, with a burner, of a valve, an expandible and contractible chamber located within said burner, and a dia- 15 phragm or equivalent means closing the lower end thereof and bearing on the valve, all of which are more fully pointed out in the following specification and claim, and illustrated in 20 the accompanying drawings, in which—

Figure 1 is a vertical central section of a burner containing my invention, the valve being shown open. Fig. 2 is a similar view, showing the valve open and the parts in the 25 position they occupy with the gas ignited. Fig. 3 is a sectional elevation. Fig. 4 is a horizontal section in the plane $x-x$, Fig. 2. Fig. 5 is a similar section in the plane $y-y$, Fig. 1. Fig. 6 is a section of the device applied to 30 a modified form of burner.

Similar letters indicate corresponding parts.

In the drawings, the letter A designates the body of a burner, which is tapped out at one end, so that it can be secured to the gas-pipe, 35 and in its other end is fitted a suitable tip, as usual. On inspection of the drawings it will be observed that the said burner is slightly larger in diameter than ordinary burners and contains two chambers, a and a' , which are 40 separated from each other by a disk, which constitutes a seat, B, for a valve-disk, C, located within the lower chamber, a' . A central opening in the said disk or seat B allows the passage of a projection or stud, c, on the valve-disk C. The said stud protrudes into the upper chamber, a , and contains a number of longitudinal recesses, which form with the openings b in the valve-seat B passages for the entrance of the gas into the upper chamber, a , 45 Fig. 5. The stem D of the valve is provided

with a lateral portion having thereon a cam- 55 surface, d , which is adapted to be engaged by a cam, e , on the end of a spindle, E, Fig. 3, ex- tending through the burner when the valve- disk is to be depressed to supply gas. The spindle E extends through a sleeve formed in or secured to the body of the burner, and upon the inner end of said sleeve is a stop, f , against which the cam e is normally held by a spiral 60 spring, G, Fig. 3, wound about the external portion of the spindle E. The two ends of the spring are secured, respectively, to the burner and to a rigid head or button, e' , on the spindle. The tendency of this spring is to nor- 65 mally hold the cam e out of contact with the cam-surface d on the lateral portion of the valve-stem D. An encircling spring, F, con- 70 fined between the lower side of this lateral portion and a bridge, f' , in which the valve- stem is guided, holds the valve-disk C normally 75 against its seat B, and the supply of gas is shut off. By turning the head e' in the proper di- 80 rection the cam e engages with the cam-surface d and depresses the valve-disk, and when 85 said cam is in a vertical position it engages with a notch or recess, d' , in the lateral portion, so that the valve remains open.

In the upper chamber, a , is rigidly located a flask or chamber, G', the lower end of which is hermetically closed by an elastic diaphragm, 8c g, Figs. 1 and 2. This flask or chamber con- 90 tains air or any other expandible and contractible fluid, and is provided with radial exten- sions, whereby passages h , Fig. 4, are formed between it and the burner for permitting the flow of gas. The lower end of the flask or chamber is so arranged in regard to the valve that when the diaphragm is forced outward by the expansion of the fluid within the same, owing to the heat transmitted thereto from the 95 burning gas, the said diaphragm comes into contact with the projection on the valve-disk. The valve, being in the position shown in Fig. 1—that is, open—is pushed downward a trifle farther by the diaphragm and the cam e is 99 released from the notch d in the stem, which cam e is instantly turned to the position shown in Fig. 2 by the spring G and against its stop, while the valve-disk is now held from its seat by the diaphragm. As long as the gas re- 100

mains ignited the valve is thus held, but when the same is inadvertently extinguished the fluid in the flask or chamber contracts on cooling, and the valve C is moved upward and to its seat by the spring E, and the gas supply is effectually shut off.

The object of my invention is to provide a device for cutting off the supply of gas in the manner described, which is located wholly within the burner itself, and consequently cannot throw a shadow, which has been the main objection to the prior devices.

When two or more local jets are to be employed, Fig. 6, on one and the same burner, I provide the body A of the same with lateral branches A', (two or more,) in which the tips are secured, and which communicate with the interior of the said body. The expandible and contractible chamber is located in the body A, as before, and heat is communicated thereto from the combined jets.

What I claim as new, and desire to secure by Letters Patent, is—

1. The combination, with a burner, of a spring-actuated valve, a closed expandible and contractible chamber located within said burner, a cam adapted to open the valve, and a diaphragm at one end of the chamber, and constructed to engage the valve, substantially as shown and described.

2. The combination, with a burner, of a valve, a closed expandible and contractible chamber located within said burner, a diaphragm at the lower end of the chamber constructed to engage the valve, and a device for opening the valve to supply gas to the burner, substantially as shown and described.

3. The combination, with a burner, of a spring-pressed valve located in the burner, a seat for said valve, an expandible and contractible chamber located in the length of the burner and near the upper end thereof, a diaphragm closing the lower end of the chamber, a cam on a spring-actuated spindle adapted to open and hold the valve temporarily, and a projection or guide on the valve extending through the valve-seat, substantially as and for the purpose set forth.

4. The combination, with a burner, of a valve-seat, a spring-pressed valve, the stem 50 thereof having a cam-surface and a notch or recess, d', therein, a spring-pressed cam, as e, engaging said stem, means, as described, for moving the cam to open the valve and to release the same, and an expandible and contractible chamber, as G', closed by a diaphragm, substantially as shown and described.

5. The combination, with a burner, of a valve, a spring closing said valve, a closed expandible and contractible chamber located 60 within said burner and forming therewith passages for the gas, means, substantially as described, for opening and temporarily holding the said valve, and a diaphragm closing one end of the chamber and constructed to engage with the valve, substantially as shown and described.

6. The combination, with a burner, of a chamber, as G', a diaphragm, g, closing the lower end of the same, a spring-pressed valve-disk, G, opening downwardly, a valve-seat for the same, a projection on the valve-disk projecting through the seat and adapted to be engaged by the diaphragm, a stem, D, for the valve, containing a cam-surface, d, and a notch, d', a cam, e, a stop, f, for the same, a spring-pressed spindle carrying said cam, and a knob or button on the same, substantially as shown and described.

7. The combination, with a burner-body, as A, having two or more lateral branches, as A', of an expandible and contractible chamber located within said body A, a spring-actuated valve, a cam carried by a spring-actuated spindle and adapted to open the valve, and a diaphragm at the one end of the chamber and constructed to engage the valve, substantially as shown and described.

In testimony whereof I have hereunto set my hand and seal in the presence of two subscribing witnesses.

FRANZ X. WAGNER. [L. s.]
